UNITED STATES PATENT OFFICE.

JAFEW S. VAN BUREN, OF ALBANY, NEW YORK, ASSIGNOR TO RATHBONE, SARD & CO., OF SAME PLACE.

DESIGN FOR A HEATING-STOVE.

SPECIFICATION forming part of Design No. 20,784, dated May 26, 1891.

Application filed March 4, 1891. Serial No. 383,809. Term of patent 3½ years.

To all whom it may concern:

Be it known that I, JAFEW S. VAN BUREN, of Albany, in the county of Albany and State of New York, have invented certain new and useful Improvements in Designs for Stoves; and I do hereby declare the following to be a full, clear, and exact description of the invention, such as will enable others skilled in the art to which it pertains to make and use it, reference being had to the accompanying drawing, which forms part of this specification.

My invention relates to designs for stoves; and it consists in the prominent features of configuration and ornamentation which will be fully described hereinafter.

The accompanying drawing represents my design.

A is the base of the stove, and B the legs, which are ornamented with a suitable configuration. Placed upon this base A is the body C of the stove, about the center of the front of which is an opening D, and placed in this opening is a circular stem E, which is provided with a series of leaves and small branches, which extend from opposite sides thereof. Below this opening D is a background, upon which the name of the stove is formed, and above the said opening is a con-

figuration which consists of a series of scrolls and volutes II.

The side of the body A is provided with a door L, and this door is provided with a configuration consisting of a stem F, which has extending therefrom upon opposite sides a series of scrolls and branches, which are provided with leaves, as shown.

The top I is oval in cross-section, as shown, and is provided with a configuration, as illustrated. Placed at the center of the top I is a figure J.

Having thus described my invention, I claim—

1. In a design for a stove, the front thereof, substantially as herein shown and described. 45
2. In a design for a stove, the top thereof, substantially as herein shown and described.
3. In a design for a stove, the side thereof, substantially as herein shown and described.
4. A design for a stove, substantially as 50 herein shown and described.

In testimony whereof I affix my signature in presence of two witnesses.

JAFEW S. VAN BUREN.
